UNITED STATES PATENT OFFICE.

WILLIAM TIVENDALE, OF CLYDEBANK, SCOTLAND, ASSIGNOR TO THE SINGER MANUFACTURING COMPANY, OF ELIZABETH, NEW JERSEY, A CORPORATION OF NEW JERSEY.

NEEDLE-STRAIGHTENING MACHINE.

Application filed January 24, 1925, Serial No. 4,378, and in Great Britain February 13, 1924.

This invention relates to machines for straightening sewing machine needles and the like, as exemplified for instance by the disclosure in my prior Patent No. 1,164,683, 5 of December 21, 1915, and in Patent No. 1,125,706, of January 19, 1915, to H. E. Noon. The primary object of the present invention is to provide a machine of this character capable of increased production over machines of prior constructions.

In its preferred form, the present improved machine includes a needle-hopper pivotally supported upon the machine frame, whereby the hopper may be at will swung 15 out of operative position, for instance, to quickly relieve any jamming of needles between the hopper and needle-feeding means. Means are provided for successively delivering needles from the hopper to two substantially parallel conveyor-screws of opposite hand and rotating in opposite directions, the needles being deposited upon a rest-bar and a supporting ledge spaced therefrom, whereby the needles are advanced laterally by 20 said conveyor-screws. A sectional pressure is opposed to a portion of the length of the rest-bar, said presser yieldingly engaging the needle-shanks whereby a friction facing on the presser puts a drag on the top side 25 of said shanks and causes the advancing needles to rotate axially. The axially rotating needles are advanced by the conveyor screws past a plurality of hammering stations, each including a peening hammer, an 30 opposed anvil and a hammer-blow controlling mechanism substantially as fully disclosed in Patent No. 1,125,706 before referred to. The hammers individually and 35 successively act on different portions of the length of each needle; in the present instance the first hammer acts to straighten the blade immediately adjacent the needle-shank; the second hammer acts upon the 40 blade intermediate the shank and point, while a third hammer acts upon the blade closer to the point thereof. The opposed 45 rest-bar and presser terminate above an opening in the machine table past the last hammering station, whereby the straightened needles are free to drop through said 50 opening into a suitable receptacle.

In the accompanying drawings, Fig. 1 is a top plan view of a multiple hammer needle-straightening machine constituting a preferred embodiment of the present invention. Fig. 2 is an end elevation of a portion of the machine as viewed from the left in Fig. 1. Fig. 3 is an end elevation of a portion of the machine as viewed from the right in Fig. 1. Fig. 4 is a sectional view 60 substantially on the line A—A of Fig. 1. Fig. 5 is a sectional view substantially on the line B—B of Fig. 1. Fig. 6 is a sectional view substantially on the line C—C of Fig. 1. Fig. 7 is a sectional view substantially on the line D—D of Fig. 1. Fig. 8 is a sectional view substantially on the line E—E of Fig. 7. Figs. 9 and 10 are detail views of one of the anvils.

Referring to the drawings, the operative 70 mechanism of the present improved needle-straightening machine is mounted upon a table 1, supported by suitable legs 2. Projecting laterally from the table 1 is a stud-shaft 3 upon which a driving pulley 4 and a 75 spur-gear 5 are journaled for unison rotation. The driving pulley 4 may have belt connections with any suitable power source, while the spur-gear 5 meshes with a similar gear 6 secured upon the projecting end 7 80 of a needle conveyor-screw 8. The screw 8 is journaled adjacent one end in a bearing-bracket 9 adjustably mounted on the table 1 and is supported at its opposite end by a pintle 10 suitably secured in an adjustable extension 11 of a bearing bracket 12. A conveyor-screw 13 is disposed in substantial axial parallelism and in spaced relation with respect to the conveyor-screw 8, the top of the screw 13 being approximately 85 at the level of the axis of screw 8. The conveyor-screw 13 is supported at one end by a pintle 14 suitably fixed in an adjustable bracket 15 mounted upon the table 1 and is journaled at its opposite end in a bearing-bracket 16 adjustably secured upon the table 1. Mounted upon one end of the conveyor-screw 13 is a spur-gear 17 driven from a spur-gear 18, secured upon the conveyor-screw 8, by means of intermeshing intermediate gears 19 and 20 supported by adjacent brackets 21 and 22 adjustably mounted 95 100

upon the table 1. It will be apparent that by means of the described gearing the screws 8 and 13 rotate in opposite directions, said gearing having a ratio whereby said screws 5 rotate at equal speeds upon rotation of the pulley 4. The screws 8 and 13 are of opposite hand, their prime function being to act in conjunction to advance the needles laterally past a multiple of hammers, as will 10 hereinafter appear.

While the needles to be straightened may be manually supplied to the conveyor-screws, the present machine includes means for automatically supplying the needles to said screws. Said means comprises a needle hopper 23 having inclined side walls, as 24, provided with vertical slots 25; a relatively fixed end wall 26, and an adjustable end wall 27 carried by a supporting-bar 28 adjustably 20 secured by means of a set-screw 29 in an aperture provided in a vertical member 30 of a hopper-frame 31. The hopper-frame 31 is pivotally supported upon the table 1, whereby the hopper 23 may be at will swung 25 out of operative position. To this end the hopper-frame 31 is provided with spaced apertured ears 32 and 33, in which are fixed the pintles 34 and 35 journaled in conically apertured bushings 36 and 37 provided in a bearing-bracket 38 suitably secured upon the table 1. The hopper-frame 31 has a base 39 which rests upon the table 1, being held in position thereupon by a clamp-plate 40, a screw-bolt 41 and a clamp-nut 35 42. By releasing the clamp-nut 42, the hopper-frame 31 may evidently be swung about the axis of the pintles 34, 35 out of operative position.

Secured in a suitable aperture provided 40 in the vertical member 30 of the hopper-frame is a flanged bushing 43 according a journal for a shaft 44 carrying a needle delivering barrel 45. Carried by the reduced outer end of the shaft 44 is a spur-gear 46 driven from a similar gear 47 carried by a counter-shaft 48 journaled in bearing brackets 49 and 12 supported by the table 1. The counter-shaft 48 carries a worm-wheel 51 driven by a worm 52 which is fixed upon the end of conveyor-screw 8. Upon operation of the machine, the needle-delivering barrel 45 is therefore constantly rotating in the operative position of the hopper-frame and inasmuch as the brackets 49 and 12 are 55 independent of said frame, the latter may be readily swung away from the driving mechanism of the barrel-shaft 44. Fixed upon the stationary bushing 43 is a needle-blade supporting sleeve 53 which together 60 with the needle-shank supporting barrel 45 closes the bottom of the hopper 23 and therefore constitutes the hopper-base.

Rising from the lateral arm 39 of the hopper-frame are two vertically apertured 65 bosses 54 and 55 in which are slidably

mounted the vertically disposed guide-bars 56 and 57 having heads as 58 and 59 upon the upper ends thereof. Mounted in a suitable horizontal guideway 60 provided by the head 58 so as to be slidable transversely 70 of the length of the bar 56 is a holder 61 in which are secured by nuts, as 62 the reduced ends of parallel pressure-bars 63, extending forwardly through the slots 25 of the hopper 23. The head 59 similarly carries pressure-bars 64 which project through said slots 25, while extending rearwardly from the heads 58 and 59 are handles 65 and 66. In the operation of the machine, one pair of pressure-bars as for instance pressure-bars 80 63 are employed to bear upon the needles in the hopper until said hopper is partly emptied, whereupon a further supply of needles is put into the hopper above said pressure-bars 63 and held under control by 85 the other pair of pressure-bars 64. The pressure-bars 63 are then withdrawn from the hopper by pulling upon the handle 65 to cause a sliding movement of the holder 61 in the guideway 60 of the head 58, whereupon 90 said bars 63 may be employed to control the succeeding needle-supply, etc. Pressure for the guide-bars 56 and 57 may be obtained in any suitable manner, as for instance, by means of weights 67 (only one 95 of which is shown) attached to said guide-bars below the table 1.

The needles are successively delivered from the hopper 23 to the conveyor-screws 8 and 13 by the barrel 45, which is provided 100 with peripheral grooves or pockets 68 for reception of the shanks of the needles, the needle-blades as before mentioned being sustained by the sleeve 53. Secured to the lower edge of one of the side walls 24 of 105 the hopper is a curved guard-plate 69 which partially surrounds the barrel 45 and confines the needles within the grooves 68 during their movement to the delivering point. To insure that the needles are delivered 110 from the pockets 68 at the proper time, there is provided a stripper-plate 70, which is secured to the lower edge of the other inclined hopper-wall 24 and has a nose 71 which projects into a circumferential groove 115 72 provided in the barrel 45. A supplemental side wall is provided for the hopper 23 adjacent the barrel 45, this supplemental wall being constituted by a segmental flange 73 having a shank 74 secured upon 120 the bracket 12 by means of a screw-bolt 75.

When the needles are deflected from the barrel 45, the shanks 76 thereof are deposited upon a rest-bar 77 situated between the conveyor-screws 8 and 13 almost the entire 125 length thereof, while the blades 78 of the needles overlie a supporting ledge 79. The rest-bar 77 is adjustably secured by screw-bolts 80 upon a plurality of angle-brackets 81 upon the table 1, while the supporting 130

ledge 79 is sustained by the rest-bar 77 through the intermediary of spacing blocks 82. The ledge 79, however, extends from the receiving end of the conveyor-screws 5 only to a point adjacent the first anvil, to be later described. The upper surface of the rest-bar 77 is flat and the height of said surface is such that the shank end of a needle resting thereupon is at the level 10 substantially, of the axis of the screw 8, whereby said shank end of the needle follows the groove of said screw and is held against longitudinal movement in one direction by the base of the screw-threads. 15 The blade 78 of the needle overlies the screw 13 and follows the groove thereof and it will be apparent that the combined action of said screws 8 and 13 is to advance the needles laterally, with said needles maintained substantially at right angles to the 20 axis of the screws, the points of the needles being preferably very slightly in advance of the shanks thereof relatively to the direction of travel. It will be observed that 25 the receiving end of the screws 8 and 13 are of slow pitch, merging into threaded portions of more rapid pitch past the several hammering stations.

Overlying the rest-bar 77 is a sectional 30 presser comprising a plurality of aligned presser-plates 83, each of which is secured by screws as 84 upon a presser-lever 85. The presser-levers 85 are each supported for pivotal movement by a fulcrum-pin 86 bridging spaced ears of an angle-bracket 35 87 adjustably secured upon the table 1. Said angle-brackets 87 each carry a stop-plate 88 between which and a presser-lever 85 is interposed a coil expansion spring 89. 40 The action of the springs 89 of each of the pressers is preferably limited by a stop-screw 88' adjustably carried by a presser-lever 85 and bearing upon the stop-plate 88. The under side of each of the presser-plates 45 83 has a facing 90 of rubber or other suitable friction material to put a drag on the top side of the needle-shanks to cause rotation of the needles as they are advanced by the conveyor-screws between the presser- 50 plates 83 and the rest-bar 77. By means of the described construction each of the pressers may yield independently of each other.

The mechanism employed for actuating 55 and controlling each of the hammers is preferably substantially as fully disclosed in the prior U. S. Patent No. 1,125,706 hereinbefore referred to, the entire hammer actuating and controlling mechanism being mounted 60 upon an auxiliary frame 91 supported upon the table 1 for bodily and angular adjustment toward and from the conveyor-screws 8, 13. Referring more particularly to Figs. 1 and 6 of the drawings, the auxiliary frame 91 is formed with a rearward 65 extension 92 provided with a rectangular slot 93 closed at its outer end by a cap-plate 94 secured by screws, as 95, upon the end of the frame-extension 92. Slidably disposed in the slot 93 is a guide-block 96 70 into which is threaded a horizontal adjusting screw 97 of which the forward unthreaded end is journaled in an aperture 98 provided in the frame-extension 92 and of which the unthreaded shank is journaled in 75 the cap-plate 94. The screw 97 is held against endwise movement with respect to the frame-extension 92 by providing said screw with a collar 99 held against one side of the cap-plate 94 by securing a manipulating knob 100 upon the screw-shank at the opposite side of the said cap-plate. The guide-block 96 is rigid with a hinge-pin 101 disposed in an aperture 102 provided eccentrically in a circularly adjustable bushing 103 journaled in a depending boss 104 on the table 1. The bushing 103 is formed with an end-flange 105, bearing against the under side of the boss 104 and provided with a plurality of apertures 106 whereby 80 a suitable tool may be employed for adjusting the bushing. Secured upon the lower end of the hinge-pin 101 is a collar 85 107 and threaded upon the upper end of the hinge-pin 101 above the guide-block 96 90 is a nut 108 by means of which the hinge-pin and the bushing 103 are secured in position; the bushing being additionally secured by means of a set-screw 109.

The auxiliary frame 91 is also provided 100 with lateral ears 110 into which are threaded the securing bolts 111 of which the heads 112 bear against the under side of the table 1 and the shanks pass through enlarged circular apertures 113 formed in 105 said table. The reduced and squared upper ends of the bolts 111 each receive a similarly apertured dog-head 114, whereby said bolts may be loosened or tightened by manipulation of said dog-heads 114, 110 which are secured by lock-nuts 115. Bearing against opposite sides of the auxiliary frame 91 are horizontal adjusting screws 116 carried by brackets 117 on the table 1. The described construction evidently 115 provides for a variety of adjustments of the frame 91. For instance, by loosening the bolt 111 and the nut 108, the frame 91 may be adjusted in a right line toward or from the conveyor-screws by manipulating the knob 100, by reason of the fact that the adjusting screw 97 is held against endwise movement with respect to the frame 91 and is threaded into the relatively 120 stationary guide-block 96. An accurate angular adjustment may be obtained by manipulating the side adjusting screws 116 to swing the frame about the hinge-pin 101, while a combination adjustment may be obtained by rotating the bushing 103 125 120

which eccentrically carries the hinge-pin 101.

Secured upon the auxiliary frame 91 are a plurality of spaced bearing-standards 118 in which is journaled a hammer-actuating shaft 119 carrying at one end a belt-pulley 120, which may have belt connections with any suitable power-source. Secured upon the shaft 119 between said standards 118 are three cam-wheels 121 formed with a series of peripheral teeth 122. Also journaled in said standards is a hammer-rock-shaft 123, upon which are secured the split-hubs 124 having rearwardly extending curved arms 125 adapted to have a wiping engagement with the cam-teeth 122. Extending forwardly from each of said hubs 124 is an arm 126 formed on its upper side with a plurality of notches 127 to 20 receive the upper loop of a tension spring 128 whose lower end is suitably attached to the frame 91. The springs 128 serve to yeldingly maintain the arms 125 in operative relation with the hammer-retracting cam-wheels 121 and to impart peening impacts to the hammers. Suitably secured upon the hammer rock-shaft adjacent each of the arms 125 is the hub 129 of a hammer-helve 130 carrying at its free end a 30 hammer-head 131. The hammer-helvles 130 are of unequal lengths, whereby the hammers act upon the needles at different portions of the length thereof.

The degree of hammer-impact is directly controlled by the needles, there being provided in the present machine an individual controlling mechanism for each hammer. This controlling mechanism is constructed and operates substantially as disclosed in 40 said prior Patent No. 1,125,706 comprising, generally, a feeler-contact device 132 which influences a vibratory lever 133 to which is secured a resilient stem 134 carrying the active member 135 of the impact regulator. The member 135 is interposed between a striking shoulder 136, formed on a lateral wing 137 of each of the hammer-helve hubs 129, and a fixed abutment 138 provided on the bearing- 50 standards 118 adjacent said hubs 129.

Adjacent the paths of reciprocatory movement of each of the hammers is disposed an anvil comprising an angle-piece 139, 140, of which the member 139 is secured for 55 vertical adjustment upon a bracket 141 by means of a screw 142 passing through an elongated slot 143 provided in said bracket. In order to conveniently effect the required vertical adjustment of each of the 60 anvils, an adjusting screw 144 is threaded into each of the members 140 of said anvils, said screws 144 bearing upon the frame 91. Each of the brackets 141 is formed with elongated slots 145 entered by screws 65 146 whereby said brackets are secured for

individual horizontal adjustment upon the frame 91. As previously explained, the supporting ledge 79 terminates immediately adjacent the first of the anvil-brackets 141, for the subsequent control of the needles 70 by the pressers 83 obviates any further necessity for supporting the advancing needles adjacent the points thereof.

The rest-bar 77 and the rearmost presser 75 83 extend slightly beyond the last hammering station, i. e., to a point above an opening 147 formed in the table 1, whereby the straightened needles are free to drop through said opening 147 into a suitable receptacle (not shown).

Means are provided for instantly stopping the operation of the needle supplying and advancing mechanism when from any cause this action is desirable. This stopping means comprises a shaft 148 disposed below the table 1 and journaled in suitable bearings provided for the purpose. Secured to one end of the shaft 148 is a stop-arm 149 of which the end 150 is adapted to engage the shank of a stop-screw 151 upon the driving-pulley 4 when the knob 152 upon the opposite end of the shaft 148 is manipulated for this purpose. To insure the proper position of the stop arm 149 with respect to the screw 151 when it 95 is desired to render the same effective, the hub of the knob 152 is provided with a stop-shoulder 153 adapted to engage a pin 154 projecting from the side of the table 1.

The operation of the machine will be apparent from the detailed description thereof herein. The needles are successively delivered from the hopper 23 by the barrel 45 to the conveyor-screws 8, 13, being supported by the rest-bar 77 and the ledge 79. 100 The screws 8, 13, advance the needles laterally, first somewhat slowly and then relatively faster with the points of the needles very slightly in advance of the shanks thereof. The shanks of the advancing needles 105 pass under the first of the alined pressers 83 whereupon the friction facing 90 of said pressers induces axial rotation of the needles. The rotating needles advance past the several hammering stations, the individual 110 hammers acting upon the needles in the same manner as in the machine of Patent No. 1,125,706, with the exception that they individually act upon their respective portions 115 of the length of the needle-blades, as explained. The needles are advanced to the hammers so closely in succession that each hammer is practically constantly acting to straighten needles, whereby the production rate is increased over prior machines of this 120 character.

Having thus set forth the nature of the invention, what I claim herein is—

1. A needle-straightening machine having a plurality of hammers arranged to indi- 125 130

- ividually act upon each of the needles at different portions of the length thereof, and means for relatively feeding the needles and hammers during effective needle-straightening operations of said hammers.
2. A needle-straightening machine having a plurality of hammers arranged to individually act upon each of the needles at different portions of the length thereof, and means for rotating the needles during effective needle-straightening operations of said hammers.
3. A needle-straightening machine having a plurality of hammers arranged to individually act upon each of the needles at different portions of the length thereof, and means for relatively feeding the needles and hammers and for rotating the needles during effective needle-straightening operations of said hammers.
4. A needle-straightening machine having a plurality of hammers arranged to successively act upon each of the needles at different portions of the length thereof, and means for relatively feeding the needles and hammers during effective needle-straightening operations of said hammers.
5. A needle-straightening machine having a plurality of hammers arranged to successively act upon the needles at different portions of the length thereof, and means for rotating the needles axially during effective needle-straightening operations of said hammers.
6. A needle-straightening machine having a plurality of hammers arranged to successively act upon the needles, and means for feeding the needles laterally past the hammers during effective needle-straightening operations thereof.
7. A needle-straightening machine having a plurality of hammers arranged to act upon the needles at different portions of the length thereof, and means for feeding the needles laterally past the hammers and for rotating the needles axially during the lateral movement thereof.
8. A needle-straightening machine having a plurality of hammers arranged to successively act upon each of the needles, and means for rotating the needles during effective needle-straightening operations of the hammers thereupon.
9. A needle-straightening machine having a plurality of hammers arranged to act upon the needles, and uninterruptedly acting feeding means continuously advancing the needles past said hammers.
10. A needle-straightening machine having a plurality of hammers arranged to act upon the needles, continuously acting feeding means for advancing the needles past said hammers, and means for inducing rotation of the advancing needles during the feeding movement thereof.
11. A needle-straightening machine having a plurality of hammers arranged to act upon the needles, substantially parallel conveyor-screws for feeding the needles past said hammers, and means for rotating said conveyor-screws.
12. A needle-straightening machine having a plurality of hammers arranged to act upon the needles, substantially parallel conveyor-screws of opposite hand for feeding the needles past said hammers, and means for continuously rotating said conveyor-screws.
13. A needle-straightening machine including a hammer, means for advancing needles past said hammer comprising substantially parallel conveyor-screws of opposite hand, means for supporting the advancing needles substantially at the level of the axis of one of the conveyor-screws, and means for rotating said screws.
14. A needle-straightening machine including a hammer, means for advancing needles past said hammer comprising substantially parallel conveyor-screws of opposite hand, means disposed between said screws for supporting the advancing needles substantially at the level of the axis of one of the screws, and means for rotating said conveyor-screws.
15. A needle-straightening machine including a hammer, means for advancing needles past said hammer comprising substantially parallel conveyor-screws of opposite hand, means disposed between said screws for supporting the advancing needles substantially at the level of the axis of one of the screws, means opposed to said supporting means for inducing rotation of the advancing needles, and means for rotating said conveyor-screws.
16. A needle-straightening machine including a hammer, means for advancing needles past said hammer comprising substantially parallel conveyor-screws, needle-supporting means disposed between said conveyor-screws, a presser opposed to said supporting means comprising a plurality of alined sections yielding independently of each other, and means for rotating said conveyor-screws.
17. A needle-straightening machine having a plurality of hammers arranged to successively act upon the needles, feeding means for advancing the needles past said hammers, means for inducing rotation of the advancing needles comprising a plurality of alined presser-sections, and means for causing said presser-sections to yieldingly engage the needles independently of each other.
18. A needle-straightening machine having a plurality of hammers arranged to successively act upon the needles, feeding means for laterally advancing the needles past said

hammers, supporting means for the advancing needles, and means opposed to said supporting means for inducing rotation of the advancing needles comprising a plurality of 5 aligned spring-pressed presser-sections yieldingly engaging the needles independently of each other.

19. A needle-straightening machine including a hammer, means for advancing needles laterally past said hammer comprising substantially parallel conveyor-screws, means for rotating said screws, and means for supporting the advancing needles substantially at the level of the axis of one of the conveyor-screws, said means for supporting the needles terminating at a point between the hammer and the end of the effective portions of said screws to permit discharge of the straightened needles therefrom.

20. A needle-straightening machine including a hammer, feeding means for advancing needles past said hammer comprising substantially parallel conveyor-screws of opposite hand, needle supporting means disposed between said conveyor-screws, a friction faced presser-plate opposed to said supporting means, a presser-lever carrying said presser-plate, means for causing the presser-plate to yieldingly engage the needles, and 30 an adjustable stop for limiting the needle-engaging movement of said presser-plate.

21. A needle-straightening machine including a hammer, feeding means for laterally advancing needles past said hammer comprising substantially parallel conveyor-screws, a needle supply hopper, and means for automatically delivering needles from said hopper to the conveyor-screws.

22. A needle-straightening machine including a hammer, feeding means for laterally advancing needles past said hammer comprising substantially parallel conveyor-screws, a needle-supply hopper, means for automatically delivering needles from said hopper to the conveyor-screws in the operative position of said hopper, and means permitting shifting of said hopper to an in-operative position.

23. A needle-straightening machine including a hammer, feeding means for laterally advancing needles to said hammer comprising substantially parallel conveyor-screws, a needle-supply hopper, a hopper-frame sustaining said hopper, a pivotal support for said hopper-frame permitting the swinging of the hopper from an operative to an in-operative position, and means for delivering needles from said hopper to said needle-feeding means.

24. In a needle-straightening machine, the combination with a supporting table, needle-feeding means, and a needle-straightening mechanism, of an auxiliary frame sustaining said needle-straightening mechanism, and means for securing said auxiliary frame up-

on said table for bodily adjustment of the needle-straightening mechanism relatively to said needle-feeding means.

25. In a needle-straightening machine, in combination, a supporting table, a needle support, an auxiliary frame supported by said table, a needle-straightening mechanism mounted upon said auxiliary frame including a vibratory hammer and hammer-actuating and controlling means, and means for adjusting the auxiliary frame in a right line upon said table relatively to said needle-support.

26. In a needle-straightening machine, in combination, a supporting table, a needle-support, an auxiliary frame supported by said table, a needle-straightening mechanism mounted upon said auxiliary frame including a vibratory hammer and hammer-actuating and controlling means, and means for permitting angular adjustment of the auxiliary frame upon said table relatively to said needle-support.

27. In a needle-straightening machine, in combination, a supporting table, a needle-support, an auxiliary frame supported by said table, a needle-straightening mechanism mounted upon said auxiliary frame including an anvil, a vibratory hammer, and hammer-actuating and controlling means, and means permitting relative adjustment of said auxiliary frame and needle-support.

28. In a needle-straightening machine, in combination, a supporting table, an auxiliary frame supported by said table, a gang-hammer needle-straightening mechanism mounted upon said auxiliary frame, and means permitting adjustment of the auxiliary frame upon said table to effect a unit adjustment of said straightening mechanism.

29. In a needle-straightening machine, in combination, a supporting table, an auxiliary frame supported by said table, a gang-hammer needle-straightening mechanism mounted upon said auxiliary frame, needle-feeding means for advancing the needles laterally past the hammers of said straightening mechanism, and means permitting relative adjustment of said auxiliary frame and needle-feeding means.

30. A needle-straightening machine having a plurality of hammers arranged to successively act upon the needles, means for feeding the needles laterally past said hammers during straightening operations thereof, means for actuating said hammers, and means for controlling the degree of impact of the hammers independently of each other.

31. A needle-straightening machine having a needle-straightening mechanism, means for feeding needles past said straightening mechanism comprising substantially parallel conveyor-screws, and means for automatically delivering needles to said con-

- veyor-screws, the threads of said conveyor-screws merging from a relatively slow pitch at the point of delivery of the needles thereto into a more rapid pitch adjacent the straightening mechanism.
32. A needle-straightening machine having needle-straightening mechanism, means for feeding needles to said straightening mechanism comprising a needle-shank advancing conveyor-screw and a needle-blade advancing conveyor-screw substantially parallel to said shank advancing screw, and means for supporting the needle substantially at the level of the axis of the needle-shank advancing screw, said blade advancing screw having a relatively smaller diameter than the shank-advancing screw.
33. A needle-straightening machine having needle-straightening mechanism, means for feeding needles to said straightening mechanism comprising a needle-shank advancing conveyor-screw and a needle-blade advancing conveyor-screw substantially parallel to said shank advancing screw, and means for supporting the needle substantially at the level of the axis of the needle-shank advancing screw to overlie the blade advancing screw.
34. A needle-straightening machine having a needle-straightening mechanism, and means for continuously feeding needles past said straightening mechanism comprising conveyor-screw means, the threads of said conveyor-screw means merging from a relatively slow-feeding pitch into a more rapid-feeding pitch adjacent the straightening mechanism.
35. A needle-straightening machine having a plurality of hammers arranged to act upon a needle at different needle-straightening stations, means for feeding a needle from one to another of said stations, and means for rotating the needles during effective needle-straightening operations of said hammers.
36. A needle-straightening machine hav-
- ing a plurality of hammers arranged to act upon a needle at different needle-straightening stations, means for feeding a needle from one to another of said stations, means for rotating the needles during effective needle-straightening operations of said hammers, and hammer impact controlling means including feeler devices arranged one at each station.
37. In a needle-straightening machine, an anvil, a hammer, hammer actuating means, hammer-impact controlling means including a feeler, and means for feeding a needle sidewise over said anvil during the needle-straightening operation of said hammer.
38. In a needle-straightening machine, means for feeding needles sidewise along a prescribed path, and a plurality of hammers arranged to act at different stations lengthwise of said path and in different zones widthwise of said path, the hammer initially acting upon a needle having its zone of action farthest removed from the point of the advancing needle.
39. In a needle-straightening machine, means for feeding needles sidewise along a prescribed path, and a plurality of hammers arranged to act upon the needles at different stations lengthwise of said path and in different zones widthwise of said path progressively approaching the point of an advancing needle.
40. In a needle-straightening machine, means for feeding needles sidewise along a prescribed path, a plurality of hammers arranged to act upon the needles at different stations lengthwise of said path and in different zones widthwise of said path progressively approaching the point of an advancing needle, and hammer-impact controlling means including feeler devices arranged one at each station and in different zones widthwise of said path.

In testimony whereof, I have signed my name to this specification.

WILLIAM TIVENDALE.
